UNITED STATES PATENT OFFICE.

ALVIN EDSTROM, OF LOS ANGELES, CALIFORNIA.

FORD TIMER.

Application filed June 23, 1925. Serial No. 39,039.

To all whom it may concern:

Be it known that I, ALVIN EDSTROM, a citizen of the United States, residing at Los Angeles, in the county of Los Angeles and 5 State of California, have invented new and useful Improvements in Ford Timers, of which the following is a specification.

My invention is an improvement in timers or so-called timing gear on electric generators for automobile timing or distributing systems.

My invention is a particular adaptation of a timing gear to the generator as used on the Ford automobile; and enables me to 15 utilize a distributor in replacement of the present commutator or timer as now utilized on the Ford automobile.

My invention therefore comprises a sleeve or collar which may be attached to the end 20 of the present generator casing as used on the Ford automobile and I utilize a special worm and worm gear drive to a vertical position distributor. The distributor box is of a standard type and may be attached to 25 the vertical shaft. The worm pinion forms the bearing for the generator shaft by means of a socket, and by an extension beyond the socket forms a shaft upon which the driving gear is secured. In this manner the generator 30 may be driven as at present through the usual drive gears and the motion is carried through the vertical shaft through the distributor. The present generator cap is utilized with ball bearings to support the 35 end of the present generator shaft.

My invention will be more readily understood from the following description and drawings in which:—

Figure 1 is a side elevation of the present 40 generator as utilized on Ford automobiles;

Fig. 2 is a side elevation of the generator of Fig. 1 with my timing gear installed on the end of the generator casing;

Fig. 3 is a vertical transverse section of 45 Fig. 2 on the line 3—3 in the direction of the arrows, showing a cross section of the collar or sleeve extension of the generator casing and the vertical timing shaft mounted therein;

Fig. 4 is a longitudinal section of Fig. 3 in the direction of the arrows on the line 50 4—4;

Fig. 5 is a longitudinal elevation of the driving pinion socket and extension shaft to drive the vertical timer shaft. 55

A standard generator such as used on the Ford automobile is shown in Fig. 1, in which the cylindrical generator casing is designated by the numeral 1, having a cap 2, secured to the casing by screw threaded studs 3. The boss 4 forming part of the cap 2 houses the standard roller or ball bearing as utilized in the present generator for the generator shaft. A drive gear 5 is keyed on the end of the shaft. 60

Referring to Fig. 2, the casing portion 1, the cap 2, boss 4 and gear 5 are the same as described in connection with Fig. 1. A collar or sleeve 6 is introduced between the end 7 of the casing and the inner surface 8 of the cap. This collar or sleeve is shown in detail in Figs. 3 and 4 and is provided at both ends with a recessed peripheral edge as indicated by the numeral 9, to engage the present casing cap. The sleeve has a downwardly extending boss 10 on the inner surface and a projection 11 extending upwardly on its outer surface, the projection and boss being in vertical alinement. An aperture 12 is drilled through the boss 10, the body portion 13 of the sleeve and through the projection 11, the latter having a counter-sunk enlargement or recess 14 for a purpose which will be hereafter described. 70

The distributor 15 indicated in Fig. 2 by 80 85 an exterior view is of a standard type and is shown as secured by a stud 16 to the distributor shaft 17, which latter extends downwardly through the drilled aperture 12 which forms a bearing or journal for the shaft and has a collar 18 fitting in the recess 14 and seated on the shoulder 19. A skewed gear 20 which may be in the form of a worm wheel is secured to the lower end of the distributor shaft preferably by a 90 pin 21.

The driving gear 22 which may be in the form of a skewed gear to mesh with gear 20 or a worm, is shown in detail in Figs. 3, 4 and 5 and has an elongated socket 23 100 formed integral with the gear and an extension shaft 24 extending beyond the base 25 of the socket. The generator is designated by the numeral 26 and has an armature

shaft 27 to which normally the gear 5 is secured on the end indicated by the numeral 28. The driving gear with its socket is keyed onto this end of the shaft by means 5 of a key 29 and held thereon by a pin 30 extending through the enlarged section 31 of the socket.

The present cap 2 is secured to the casing 1 by a series of bolts 32 which extend completely 10 through the sleeve and fit into the same threaded holes provided for the studs 3, the only difference being that the bolts 32 are longer than the studs 3. An anti-friction bearing designated generally by the 15 numeral 33 is housed in the boss 4 of the cap and consists of ball bearings 34 operating in an outer ball race 35 fitted into the boss and an inner ball race 36 pressed on the outside of the socket portion 23 of the driving gear 20 assembly. In this manner the shaft 27 is held rotatably in proper alignment by being secured in the socket and having the anti-friction bearing on the exterior thereof.

The usual drive gear 5 is keyed on the extension shaft 24 by means of a key 37, which is secured by a pin through the pin hole 38.

The operation of my timing gear for a distributor it is believed will be obvious as the usual gear 5 drives the generator through 30 the medium of the extension shaft 24, the socket 23 keyed on the shaft 27 and hence the generator 26. The skewed gears 20 and 22 which as above described, may be in the form of a worm and worm gear, drive the 35 distributor shaft 17 and hence the distributor mounted on the upper end thereof.

My invention may be considerably modified to adapt it to different types of electric generators as used on automobiles or the like, to operate distributors or lead the drive for some other purpose. It will also be obvious that my invention applies generally to a geared transmission in which a sleeve may be attached to the end of the casing and 45 carry a driven shaft at right angles to the driving shaft by means of a driving gear which has a socket connected thereon, such socket supporting the driving shaft.

Having described my invention, what I 50 claim is:

1. A gear transmission comprising in combination a casing, a collar secured to the end of the casing, a cap attached thereto, a main shaft centrally positioned in the casing, a driving gear having a socket fitted over the end of the shaft, a bearing on the outside of the socket in the cap, a shaft extension on the

end of the socket and a driven shaft having a gear meshing with the driving gear.

2. A gear transmission as claimed in claim 1, in which the driven shaft extends laterally through the bearing in the sleeve.

3. A gear transmission as claimed in claim 1, having an anti-friction bearing in the cap supporting the socket and therefore the main shaft.

4. A gear transmission as claimed in claim 1, in which the driven shaft extends laterally through the bearing in the sleeve and having an anti-friction bearing in the cap supporting the socket and therefore the main shaft.

5. A timer comprising in combination a casing, an electric generator mounted therein having an armature shaft, a sleeve attached to the end of the casing, a cap forming a closure on the end of the sleeve, a drive gear having a socket and a shaft extension beyond the socket secured to the end of the armature shaft, a bearing in the cap for the socket, means to rotate the extension shaft and a timing shaft having a gear meshing with the driving gear.

6. A timing gear as claimed in claim 5, in which the timing shaft extends transversely through a bearing in the sleeve and has a distributor mounted on the end thereof.

7. A timing gear as claimed in claim 5, having an anti-friction bearing in the cap supporting the socket and the generator.

8. A timer comprising in combination a generator having an armature shaft, a casing in which said generator is housed, a sleeve and a cap therefor attached to the casing by bolts or the like, an anti-friction bearing in the cap, a drive gear having a socket and an extension shaft all formed integral, the socket being fitted on the end of the armature shaft and the outside of the socket being supported in the anti-friction bearing, a gear on the end of the extension shaft to rotate the drive gear and the armature, a boss formed integral with the said sleeve and extending inwardly, a distributor shaft journaled in said boss and extending outwardly beyond the sleeve and having a driven gear meshing with the driving gear.

9. A timing gear as claimed in claim 8, having a projection on the outside of the sleeve with a recess therein forming a seat for a collar on the distributor shaft.

In testimony whereof I have signed my name to this specification.

ALVIN EDSTROM.
